UNITED STATES PATENT OFFICE.

NEWELL V. DYER, OF HOLBROOK, MASSACHUSETTS, ASSIGNOR TO UNITED SHOE MACHINERY CORPORATION, OF PATERSON, NEW JERSEY, A CORPORATION OF NEW JERSEY.

MACHINE FOR MARKING MATERIALS.

1,360,379.

Specification of Letters Patent. Patented Nov. 30, 1920.

Application filed May 3, 1918. Serial No. 232,278.

To all whom it may concern:

Be it known that I, NEWELL V. DYER, a citizen of the United States, residing at Holbrook, in the county of Norfolk and State of Massachusetts, have invented certain Improvements in Machines for Marking Materials, of which the following description, in connection with the accompanying drawings, is a specification, like reference characters on the drawings indicating like parts in the several figures.

My invention relates to machines for marking various objects, and particularly to those employed in marking portions of shoes. For such work the usual practice is to arrange the stock, when cut, with the corresponding pieces of the right and left shoes of a pair together; and to identify them unmistakably before they go to the operators for assembling, there are placed upon them symbols indicating, for example, the case number, size, width, and match marks. Ordinarily, these indications are applied to the flesh side of one of the pieces of a pair, after which the symbols are similarly placed upon the other piece.

This invention has as an object the provision of a machine whereby different surfaces, as those of pairs of shoe parts, may be marked by a single operation in an effective manner.

A feature of the invention consists in a machine for marking, in which pieces are placed together and oppositely or simultaneously impressed with the symbols identifying them. When these pieces are shoe parts, the corresponding pairs of pieces are laid with their finish surfaces together, and the impressions made at the same time upon the opposite sides.

In the preferred embodiment the impression members move oppositely to exert independent pressure upon the work. This independence of effect is preferably obtained by means of separate pressure-receiving members co-operating with the impression members. To avoid interference with the placing of the work between the impression members, at least one of the pressure-receiving members is movable, so that it may be withdrawn from the line in which the work is introduced.

When the surfaces for producing the im-

pressions are so arranged upon marking members that one of a plurality may be brought into use at a time, as a further feature, the marking members bearing these surfaces are so organized that a plurality of these members may be selected and then simultaneously acting surfaces brought into position, the selecting and positioning of the plural members and surfaces being respectively by a single operation.

These and other features are more fully set forth in the following description and illustrated in the accompanying drawings, wherein

Figure 1 shows a front elevation of one embodiment of my machine;

Fig. 2 is a side elevation thereof;

Fig. 3 is a longitudinal section illustrating the impression members and their supporting and actuating elements, together with a portion of the setting mechanism;

Fig. 4 is a similar view showing the mechanism for applying the marking agent to the impression surfaces;

Fig. 5 is a broken perspective view of the setting mechanism;

Fig. 6 is a longitudinal sectional detail through one of the series of impression members; and

Fig. 7 is a detail in side elevation, showing the parts as producing their impression upon two pieces of material.

A casing 10, in which the operating elements of my improved machine are mounted, is provided at its front with a recess, at the lower side of which is a horizontal work-supporting surface or table 12. Entrance to the parts within the casing is provided for by removable panels 14 situated at the front above and below the table and also at the rear of the casing. Extending transversely of the casing are horizontal shafts 16 and 18, shown as situated just above and below the line of the table, and upon these shafts are fulcrumed levers 20 and 22, forwardly extending arms of which have fixed between them spindles 24 carrying the marking members, here shown as consisting of series of adjacent type or die disks 26. These disks have extending radially from their peripheries teeth or projections 28, at the extremities of which are surfaces for producing the impression upon the work, these

surfaces being in the form of any desired symbols, as numbers or letters. The disks are mounted to turn upon the spindles and are held at the angle to which they may be 5 adjusted by retaining members, there being one for each series of disks, common to the entire series. Each retaining member may consist of a rod 30, located within a recess 32 extending along one side of the spindle 10 and capable of engaging any one of a series of grooves, semi-circular in cross-section, formed in the openings through the disks about the spindle. To hold each rod 30 in engagement with the disk grooves, springs 15 36 are placed at each extremity, these resting in bores in the spindle and acting to force the rod outwardly.

To move the levers 20 and 22 and the stamping members carried thereby toward 20 and from the table 12 and a secondary pressure-receiving member or abutment 38, to be later described, their rear arms have projections 40 entering cam-grooves 42 in disks fixed to a transverse shaft 44 journaled 25 in the rear portion of the casing. The projections 40 may be separately fixed to the levers, as by screws. The shaft 44 has secured upon it a gear 46, with which meshes a pinion 48 fast upon a power-shaft 50 journaled at the extreme rear of the casing. On 30 this power-shaft are fast and loose pulleys 52, with which may coöperate a belt (not shown) receiving motion from some suitable source of power. The gear 46 is preferably 35 joined to the shaft 44 through a clutch, indicated at 54, this being of any suitable type, preferably adapted to cause a single rotation of the shaft upon its release by a rod 56 which may extend to a treadle (not illustrated). The cam-grooves 42 are similar in 40 form but are oppositely placed, being separated by an angle of 180 degrees, and cause the stamping disks to be simultaneously moved toward one another and the corresponding table or abutment, after which 45 they are returned to their normal positions. To allow the impression surfaces or dies to make their impressions yieldably, the rear arm of each lever 20 and 22 has a section 58, 50 pivoted at 60 upon the main lever and acting against a spring 62 interposed between the lever and section. In the rear extremities of the sections are the pins 40, and, while these are constrained to move through 55 vertical paths of unvarying lengths, the dies, by virtue of the springs 62, may yield in accordance with the thickness of work with which they are brought into contact. Firm pressure is thus assured without danger 60 of injury to the work or of breaking the marking mechanism.

The vertical alinement of the upper and lower die disks is such, that when those carried by the lever 20 are acting upon work 65 supported on the table 12, those mounted

upon the lever 22 projects through an opening 64 in the table at the rear of the upper dies and produce their impressions against the pressure-receiving member 38. To leave the space above the table 12 clear for the 70 introduction and withdrawal of stock at the beginning and end of the operation, the member 38 is movably mounted in the casing 10, it being illustrated as sliding in inclined ways 66. In the member 38 a rack 75 68 is formed, with which meshes a gear-segment 70 at the extremity of an arm 72 fast upon the shaft 16. As the lever 20 and its die disks 26 descend to produce their impression and the lever 22 and its disks rise, 80 the member 38, through the gearing 68, 70, is moved down toward the opening 64 to meet the lower impression members 26, forming an abutment which takes the impression upon the lower piece of stock equal 85 in efficacy to that furnished by the table for the upper dies. In the opposite or retreating movement of the die disks, the member 38 is withdrawn to a position at which it is clear of the space above the table, so that 90 it does not interfere with the introduction of the next piece of work.

To apply a pigment or marking agent to the dies, pads or other members 74 for carrying such agent are supported upon arms 76 95 pivoted upon a slide 78 movable in horizontal ways 80 in the frame. At its rear extremity, the slide has slotted connection with a bell-crank lever 82, fulcrumed in lugs 84 rising from the bottom of the casing. 100 The other arm of the lever has a projection 86 extending into a cam-groove 88 in a disk fixed to the cam-shaft 44. As the cam-shaft rotates and the die-levers are oscillated, the bell-crank lever reciprocates the slide 78 105 from a rearward position, at which the pads 74 are clear of the die-disks, forwardly beneath and above said disks, and in this movement projections 90 from rearward extensions of the arms 76 enter opposite 110 grooves 92, one of which is inclined upwardly and the other downwardly from the horizontal. Under the influence of these grooves, the arms 76 are swung upon their pivots on the slide, so that, as the pads reach points opposite the dies, they are pressed against said dies to apply the marking agent thereto. This occurs at the time that the stamping disks are in their normal position. Thereafter, the slide is moved back and the 115 pads withdrawn to their initial points clear of the paths through which the die-disks move in the oscillation of the levers.

In the work for which this machine is particularly designed, it is customary to impress the same symbols upon two sheets of material presented to it. I therefore furnish means for simultaneously setting the corresponding upper and lower die-disks, and also for simultaneously selecting which pair 120

of disks shall thus be adjusted, by setting means common to the respective series. In their resting positions, the teeth of the disks 26 mesh with series of toothed setting disks 94 mounted between cheeks upon the casing on the upper and lower spindles 96, 98, respectively. These spindles are journaled for rotation and for axial movement in the opposite walls of the casing, they also sliding through the disks 94. The spindle 96 may be turned by a hand wheel 100 fast upon one end, and the spindle 98 is arranged to rotate with it at the same rate by gearing consisting of sprocket-wheels 102 splined upon the spindles and a chain 104 operating over these wheels. In the hubs of the sprockets are grooves 103 into which extend projections from the frame, holding them against bodily movement. The chain 104 passes rearwardly from the sprockets 102 over idlers 106 and 108. The former is shown as turning upon the shaft 16, while the latter is rotatable upon an arm 110 pivoted upon the side of the casing and urged against the chain by a spring 112 acting to swing the arm to the right, as viewed in Fig. 2 of the drawing, thus keeping the chain properly taut. Projecting radially from each of the spindles 96 and 98 is a pin 114, which, in the axial movement of its spindle, may be brought into one of a series of recesses 116 arranged in the central opening of each disk about the spindle, there being a recess of the series opposite each tooth, and, by this engagement, the rotation of the spindles may be communicated to the disks. To simultaneously align the spindle projections with a particular pair of disks which it may be desired to turn and to confine the setting action to the pair thus selected, the spindles 96 and 98 each have connected to them by opposite end pieces 118, 118, spindles 120 and 122, all mounted to reciprocate through openings in the sides of the casing similarly to the spindles 96 and 98. The spindles 120 and 122 have teeth 124 cut on opposite sides to furnish racks, with which mesh pinions 126, 126 near the upper and lower extremities of a vertical shaft 128 journaled in bearings in the top and bottom walls of the casing, and provided at its upper extremity with a hand-wheel 130 by which it may be turned. On rotating this hand wheel, the pinions and racks shift the frames formed by the spindles and side pieces in opposite directions to bring the projections 114 into one or another of the pairs of disks 94. An index finger 132 is shown as fixed to the upper spindle 122, pointing to the disk which has been selected, that is, into which the projection 114 has been carried; and to show the operator the symbols which are upon the corresponding disks 26, the projections of the disks 94 have inscribed upon them the respective symbols.

the relations between the elements being such that when a symbol is beneath the index finger, like symbols are in marking position upon both of the corresponding disks 26. To lock against rotation all the disks 94 except the pair at the time in setting engagement with the projections 114, the spindles 122 have extended lateral projections 133, which enter between the teeth of the disks 94 and hold them from turning. Through these projections 133, corresponding to the position of the index finger, are grooves 134 of such dimensions as to permit the rotation through each of them of a single disk. If the operator wishes, for example, to set the die-disks, the index figure for which appears on the third from the left of the upper series of disks 94 in Fig. 5 of the drawings, he moves the spindle frames by turning the shaft 128 until the index finger 132 occupies a position over this third setting disk. This will move the projections 114 of both the spindles 96 and 98 into corresponding upper and lower die-disks 26, and will lock all the setting wheels 94 except the selected pair, which are aligned with the grooves 134 in the spindles 122. Then, by means of the hand wheel 100 and the gearing connecting the spindles 96 and 98, he turns the selected setting disks through the engagement of the projections 114 until the character chosen upon the third disk is beneath the index point. This indicates that the impression surfaces of both die-disks selected are in the marking position.

Assuming that my machine is to be used for the purpose of marking parts of shoes upon the flesh side of the leather, the various corresponding pieces of the shoes of a pair are arranged with the grain sides together, and the die disks are set as just described to give the desired case, size, width and match designations. The operator then lays a pair of the pieces upon the table 12, as shown in Fig. 7, and starts the operation of the machine by engaging the clutch 54. The cam mechanism first moves the pads 74 into contact with the lines of chosen characters upon the die disks, withdraws them, and then moves said disks against the work, the member 38 receiving the pressure of the lower series of disks, while the upper series acts against the table. This, at a single operation, impresses upon both pieces of the work the same identifying designation, and the cam mechanism then withdraws the die-disks and movable pressure-receiving member to prepare the machine to receive another pair of pieces. If it is not desired to mark two pieces at a single operation, one only may be operated upon by disconnecting one of the levers carrying the impression surface, preferably the lower, 22, by removing its projection 40, so that the corresponding set of dies remains inactive.

Having fully described my invention, what I claim as new and desire to secure by Letters Patent of the United States is:—

1. In a marking machine, oppositely acting marking members arranged to exert their pressure independently upon the work and means for moving both marking members toward and from the work.
2. In a marking machine, oppositely acting marking members, means for moving both marking members toward and from the work and a pressure-receiving member coöperating with each marking member.
3. In a marking machine, oppositely acting marking members, means for moving both marking members toward and from the work, and a pressure-receiving member coöperating with each marking member, one of said pressure-receiving members being fixed relatively to the marking members and the other pressure-receiving member being movable into and out of the path of a marking member.
4. In a marking machine, a work-support, oppositely movable marking members, one of which coöperates with the work support, and a pressure-receiving member movable to meet the other marking member.
5. In a marking machine, oppositely movable impression members, a pressure-receiving member coöperating with each impression member, power-actuated means for effecting the movement of the impression members, and yieldable connections between the power-actuated means and impression members.
6. In a marking machine, oppositely movable marking members, and a pressure-receiving member coöperating with each marking member, one of said pressure-receiving members being fixed and toward which a marking member moves and the other being movable oppositely to the associated marking member.
7. In a marking machine, a work-support provided with an opening, an impression member movable into contact with the work at one side of the support opening, and an impression member acting through the support opening.
8. In a marking machine, a work-support provided with an opening, an impression member movable into contact with the work at one side of the support opening, an impression member acting through the support opening, and a pressure-receiving member coöperating with the last-named impression member.
9. In a marking machine, a work-support provided with an opening, an impression member movable toward and from the work-support, an impression member acting through the support opening, and a pressure-receiving member normally separated from the work-support and being movable toward said support into coöperation with the last-named impression member.
10. In a marking machine, a pair of pivoted members, a die carried by each member, means for oscillating the members to move the dies simultaneously toward and from each other, and independent means for receiving the pressure of the dies.
11. In a marking machine, two carrier members, a die mounted upon each carrier member, operating means for the carrier members to move the dies toward and from each other, and readily separable connections between a carrier member and its operating means.
12. In a marking machine, a frame having a work support, a pair of members pivoted independently upon the frame, a series of die-disks carried by each member, and means for oscillating the members to move the dies toward and from the work support.
13. In a marking machine, a pair of pivoted members, a die carried by each member, a power-shaft, and actuating means for the members carried by the power-shaft and serving to move the dies in opposite directions.
14. In a marking machine, the combination with a casing having a work-abutment, of an abutment movable upon the casing, dies movable upon the casing into and out of coöperation with the abutment, and means for moving the dies and the movable abutment.
15. In a marking machine, the combination with a casing, of a table provided with an opening, a die coöperating with the table, and a die and pressure-receiving member movable into coöperation through the table opening.
16. In a marking machine, the combination with a casing provided with ways, of a table having an opening, a die coöperating with the table, a second die, and a slide movable in the ways, the last-named die and slide coöperating through the table opening.
17. In a marking machine, the combination with a casing provided with ways, of a table having an opening, a die coöperating with the table, a second die, a slide movable in the ways, the last-named die and slide coöperating through the table opening, a power-shaft rotatable in the casing, and means carried by the power-shaft for moving the dies and slide.
18. In a marking machine, the combination with a casing, of a table provided with an opening, levers fulcrumed in the casing and projecting at opposite sides of the table, a series of die-disks carried by each lever and coöperating with the table and table opening, and a pressure-receiving member movable into proximity with the table opening.
19. In a marking machine, the combination with a casing, of a table provided with an opening, levers fulcrumed in the casing and projecting at opposite sides of the table, a series of die-disks carried by each lever and coöperating with the table and table opening, and a pressure-receiving member movable into proximity with the table opening.

tion with a casing provided with ways, of a table having an opening, levers fulcrumed in the casing and projecting at opposite sides of the table, a series of die-disks carried by each lever and coöperating with the table and table opening, a slide mounted in the ways and being movable into proximity with the table opening, and connections between the slide and one of the levers.

20. In a marking machine, the combination with a casing provided with ways, of a table having an opening, levers fulcrumed in the casing and projecting at opposite sides of the table, a series of die-disks carried by each lever and coöperating with the table and table opening, a slide mounted in the ways and being movable into proximity with the table opening, connections between the slide and one of the levers, a power-shaft, and cams fixed to the power-shaft and co-operating with the levers.

21. In a marking machine, oppositely acting impression members, a member for applying a marking agent to each impression member, a reciprocatory support for the applying members, and guiding means for the applying members for moving them in opposite directions against the impression members in the reciprocation of the support.

22. In a marking machine, oppositely acting impression members, a reciprocatory slide, arms pivoted to the slide and carrying pads for contact with the impression members, said arms having projections, and members having grooves in which the projections move in the travel of the slide.

23. In a marking machine, oppositely acting impression members, a reciprocatory slide, arms pivoted to the slide and carrying pads for contact with the impression members, said arms having projections, and members having grooves in which the projections move in the travel of the slide, said grooves having parallel portions and oppositely inclined portions.

24. In a marking machine, oppositely acting impression members, a pressure-receiving member coöperating with each impression member, and a member for applying a marking agent to each impression member and being movable between the impression member and the corresponding pressure-receiving member.

25. In a marking machine, a pair of pivoted members, a die carried by each member, means for oscillating the members to move the dies simultaneously toward and from each other, and members for simultaneously applying a marking agent to both dies between the periods of oscillation.

26. In a marking machine, a pair of pivoted members, a die carried by each member, means for oscillating the members to move the dies simultaneously toward and from each other, members for simultane-

ously applying a marking agent to both dies between the periods of oscillation, a power-shaft, and actuating means for the pivoted members and applying members carried by the power-shaft and serving to move the dies in opposite directions and to move the applying members between the dies and toward and from said dies.

27. In a marking machine, a plurality of marking members each provided with a plurality of impression surfaces, and means constructed and arranged to select plural marking members and to set said marking members, the selecting and setting being respectively by a single operation.

28. In a marking machine, a plurality of series of marking members each provided with a plurality of impression surfaces, means for selecting a marking member in each series, means for connecting said selecting means to operate together, means for setting the marking members of both series to determine which impression surface shall be effective, and means for connecting said setting means to operate together.

29. In a marking machine, a plurality of series of marking members each member being provided with a plurality of impression surfaces, setting means associated with each series of marking members and being common to a plurality of members in said series to determine which impression surface shall be effective, and means constructed and arranged to bring the setting means of plural series simultaneously into coöperation with particular marking members.

30. In a marking machine, a plurality of series of marking members each member being provided with a plurality of impression surfaces, setting means associated with each series of marking members and being common to a plurality of members in said series to determine which impression surface shall be effective, means constructed and arranged to bring the setting means of plural series simultaneously into coöperation with particular marking members, and means for connecting said setting means to operate together.

31. In a marking machine, a plurality of marking members each provided with a plurality of impression surfaces, a setting member for each marking member, movable supports for the setting members, and means for connecting the supports to move together.

32. In a marking machine, a plurality of marking members each provided with a plurality of impression surfaces, setting members for the marking members, supports for the setting members having a plurality of movements, and means for connecting the supports to perform the movements together.

33. In a marking machine, a plurality of

marking members each provided with a plurality of impression surfaces, setting members for the marking members, supports for the setting members having a plurality of movements, and gearing for transferring the movements of one of the supports to another.

34. In a marking machine, a plurality of disks having portions corresponding to different symbols to be marked, spindles extending through the disks, and gearing connecting the spindles and arranged to impart thereto movement with and through the disks.

35. In a marking machine, a plurality of disks having portions corresponding to different symbols to be marked, spindles extending through the disks and being mounted for rotation, means constructed and arranged to rotate and reciprocate one of the spindles, and gearing connecting said spindles.

36. In a marking machine, a plurality of disks having portions corresponding to different symbols to be marked, spindles extending through the disks and being mounted for axial movement, and means including gearing constructed and arranged to move said spindles together.

37. In a marking machine, a plurality of disks having portions corresponding to dif-

ferent symbols to be marked, spindles extending through the disks and being mounted for rotation and for axial movement, and independent gearing connections for causing the spindles to share in the rotation and axial movement.

38. In a marking machine, opposite series of disks having portions corresponding to different symbols to be marked, a rotatable spindle extending through each series, a sprocket rotatable with each spindle, and a chain connecting the sprockets.

39. In a marking machine, opposite series of disks having portions corresponding to different symbols to be marked, an axially movable spindle extending through each series, a rack movable with each spindle, and a shaft having pinions engaging both racks.

40. In a marking machine, opposite series of disks having portions corresponding to different symbols to be marked, a rotatable and axially movable spindle extending through each series, a sprocket rotatable with each spindle, a chain connecting the sprockets, a rack movable with each spindle, and a shaft having pinions engaging both racks.

In testimony whereof I have signed my name to this specification.

NEWELL V. DYER.
